PROCESS FOR SEPARATING HYDRO-CARBONS

Charles E. Welling, Wilkinsburg, Pa., assignor to
Phillips Petroleum Company, a corporation of
Delaware

No Drawing. Application December 13, 1943,
Serial No. 514,157

8 Claims. (Cl. 183—115)

This invention relates to the separation of mixtures comprising close-boiling olefin hydrocarbons. More particularly, this invention relates to the selective extraction of one or more olefins from a gaseous mixture of close-boiling isomeric 5 olefins, utilizing a selective solvent in which branched olefins are more soluble than unbranched or less-branched olefins.

Large quantities of olefinic hydrocarbons are produced in various industrial processes. In general, these olefins when concentrated by known means are found to be mixtures of close-boiling structural isomers. However, it often happens that such a mixture of isomeric olefins is undesirable for special uses, as in chemical syntheses 15 of particular derivatives or products, and in such cases the known methods of separation of olefinic hydrocarbons are either inadequate or impractical from the economic standpoint.

The difficulties encountered in separating mixtures of close-boiling, isomeric olefins by fractional distillation, for instance, are readily perceived from consideration of the small differences in boiling points that frequently exist. Thus, in the case of the butenes, the following pair of compounds of almost identical boiling points is found:

Compound	Boiling point, F.
Isobutene.....	10.2
Butene-1.....	20.7

When the isomeric pentenes are considered, much the same situation is found, as is shown below.

Compound	Boiling point, F.
Pentene-1.....	86.2
2-methyl-1-butene.....	87.9
Pentene-2 (low-boiling geometrical isomer).....	96.6
Pentene-2 (high-boiling geometrical isomer).....	98.6
2-methyl-2-butene.....	101.5

In general, the number of isomeric olefins increases, and the boiling point differences decrease, for higher members of the homologous series, 50 such as hexenes.

My invention is a process for the separation

of structurally isomeric olefins of different degrees of branching one from another by contacting the olefinic mixture, in the gaseous state, with a selective solvent, specifically furfural, which effects a selective solution of the more-branched olefins in preference to the less-branched olefins. The term less-branched olefins as used herein may include straight-chain olefins. After the contacting, the dissolved olefins may be recovered from the solvent by heating, reduction of pressure, or other suitable means, and are found to contain a greater proportion of the more-branched olefin or olefins, whereas the undissolved hydrocarbon vapors are found to contain a lesser proportion of the more-branched olefins. In this manner a more or less complete segregation of the olefins in the mixture, in accordance with structure, is brought about. Although furfural and other selective solvents have 20 been proposed for use in separating different types of hydrocarbons, my invention is not concerned with such separations, but with the hitherto unknown separation of one isomeric olefin from another.

When treating a close-boiling mixture of isomeric olefins according to my invention, the process is preferably carried out by conducting the olefinic mixture, in the gaseous state, into a scrubbing tower countercurrently to the liquid solvent, so that the gas is depleted in its content of the more-branched olefins and is withdrawn at the top, and the solution containing the more-branched olefins is withdrawn at the bottom of the tower.

As will be clear to one skilled in the art, the temperature and the pressure to be employed in practicing my invention depend to a considerable extent upon the olefinic mixture to be treated. In general, it is desirable to operate at temperatures within the range 50–300° F. and at pressures somewhat below the vapor pressure of the olefinic mixture at the temperature of operation. When treating mixtures of pentenes, I have found a temperature of 150° F. and a pressure of 30 p. s. i. a. to be suitable conditions for selectively absorbing the branched pentenes in furfural.

Any known arrangement of apparatus to promote efficient contacting of gas and liquid may be employed in practicing my invention. Likewise, a scrubbing tower may be arranged with the hydrocarbon feed introduced at some point

intermediate between the point at which lean solvent is introduced and the point at which rich solvent is withdrawn, and a temperature gradient may be maintained through the tower by reboiling of the rich solvent reaching the bottom of the tower together with abstraction of heat from the gases rising to the top of the tower. As will be recognized by one skilled in the art, the amount of reboiling of rich solvent and the required efficiency of the scrubbing tower as measured by the number of theoretical gas-liquid contacts that are brought about are dependent upon the particular olefinic mixture to be treated and also upon the degree of segregation of the component olefins that is desired; when the latter factors are determined, the former may be readily established. Although the ratio of solvent to olefinic mixture to be separated depends upon the factors discussed above, I may state that ordinarily suitable mol ratios of solvent to hydrocarbon charge range from around 5:1 to 40:1.

I have found that I may employ my process for separation of isomeric olefins in mixtures even when hydrocarbons of other types, such as paraffins and diolefins are also present. I may also state that my process is particularly applicable to the separation of close-boiling mixtures of isomeric olefins that contain from four to six carbon atoms per molecule. However, when the separation of wide-boiling mixtures of isomeric olefins is to be made it sometimes happens that my process is less applicable than conventional fractionation. Thus, although I have found that of two olefins having about the same boiling point the more-branched olefin possesses relatively the greater solubility in the solvent phase of a vapor-solvent system and that the difference in solubility is enhanced if the boiling point of the more-branched olefin is higher than that of the less-branched olefin, the difference in solubility may be reduced or even overcome if the more-branched olefin is considerably lower boiling than the less-branched olefins. Therefore, I prefer to apply my process to mixtures of isomeric olefins of such a nature that the more-branched olefin or olefins that are to be preferentially dissolved in the solvent either boil above the less-branched olefins or in any event do not boil more than about 3 to 6° F. below the less-branched olefins. Thus, although my process is advantageously applicable to the separation of isobutene from butene-1, whereby isobutene is selectively dissolved in the solvent, it is not equally applicable to the separation of a mixture of isobutene and butene-2 since this mixture can be readily separated by conventional fractionation.

In employing furfural as the selective solvent in the process according to my invention, it is sometimes advantageous to add small amounts of other solvents in order to modify the properties of the furfural. Thus, for example, I may add a few per cent, usually three to five, of water to the furfural.

In order further to illustrate my invention, I may mention a practical application which is indicative of the present interest in a process capable of effecting the separation of isomeric olefins in concentrated or pure form. However, this application is not to be taken as limiting in any way the scope of my invention. This application consists in treating, according to my invention, a close-cut fraction comprising pentene-2 and 2-methyl-2-butene in order to effect separation of the mixture into a portion that is

rich in pentene-2 and an extract portion which is recovered from the solvent, that is rich in 2-methyl-2-butene. Each portion may then be subjected to thermal cracking to produce di-olefins, and the cracking conditions may be so adjusted as to obtain maximum efficiency in each case. In this way greater yields are realized from the isomeric pentenes than could be realized by thermal cracking of the original fraction, because of the considerable differences in optimum conditions for cracking these individual hydrocarbons.

In another embodiment of my invention, close-boiling isomeric olefins are separated when a paraffin is also present in the mixture. For example, a mixture of pentene-2, 2-methyl-butene-2, and n-pentane may be contacted, under suitable conditions, with the solvent. The portion recovered by stripping the enriched furfural is rich in 2-methyl-butene-2. The overhead from the extraction step containing the pentene-2 and n-pentane is passed to a second gas-liquid solvent extraction step employing furfural or another suitable solvent wherein the pentene-2 is extracted and the n-pentane removed overhead. The solvent is stripped to recover a portion rich in pentene-2. By means of my process a mixture of three or more close-boiling hydrocarbons may be separated into substantially pure fractions.

The selectivity that I have found to be exercised by the solvent of my invention as between more- and less-branched olefins is illustrated and exemplified by the following experimental observations, but the invention is not to be limited thereby.

Two sets of measurements were made to obtain the solubilities or vapor-liquid equilibria of the low-boiling geometrical isomer of pentene-2 and of 2-methyl-2-butene in furfural containing four weight per cent dissolved water. The vapor-liquid equilibrium for each olefin was measured separately; normal pentane was used as a diluent in every case. Each measurement was made in an equilibrium bomb at identical pressures and temperatures (30 p. s. i. a. and 150° F.). The measurements consisted in establishing equilibrium between the liquid furfural phase and the gaseous hydrocarbon phase under the desired conditions of temperature and pressure and then withdrawing samples from each phase and analyzing the samples. From the analyses the equilibrium or "K" constants for each hydrocarbon were calculated by dividing the mol percentage of the hydrocarbon found in the gas phase by the mol percentage of the same hydrocarbon found in the solvent phase. A similar procedure was employed in calculating the equilibrium constants for both furfural and water, save that the amounts of these materials in the gas phase were estimated from the known vapor pressures of the materials rather than determined by analysis, because of the difficulties of making accurate analyses for the small amounts involved.

The hydrocarbon mixture containing 2-methyl-2-butene was composed of 25.5 mol per cent 2-methyl-2-butene and 74.5 mol per cent n-pentane. The composition of the mixture containing the low-boiling isomer of pentene-2 was 25.1 mol per cent pentene-2 and 74.9 mol per cent n-pentane.

The compositions of the gas and liquid phases in the various systems and the calculated equilibrium constants are shown in the tabulation below. As is shown, check runs were made with each olefin.

System	Components of system	Equilibrium conditions		Gas phase, mol percent	Liq. phase, mol percent	"K" constant
		Temp., °F.	Pressure, p. s. i. a.			
A-1	2-methyl-2-butene			17.3	2.5	6.9
	n-Pentane	150	30	79.2	5.6	14.1
	Water			2.1	16.7	0.127
	Furfural			1.4	75.2	0.018
A-2	2-methyl-2-butene			18.8	2.4	7.8
	n-Pentane	150	30	77.7	5.7	13.6
	Water			2.1	16.8	0.127
	Furfural			1.4	75.1	0.018
B-1	Pentene-2			22.4	1.8	12.4
	n-Pentane	150	30	74.1	5.0	14.8
	Water			2.1	16.9	0.127
	Furfural			1.4	76.3	0.018
B-2	Pentene-2			22.2	1.9	11.7
	n-Pentane	150	30	74.2	4.5	16.5
	Water			2.2	17.1	0.127
	Furfural			1.4	76.6	0.018

The average "K" constant for 2-methyl-2-butene in systems A-1 and A-2 is seen to be 7.35, whereas the average "K" constant for the low-boiling geometrical isomer of pentene-2 in systems B-1 and B-2 is seen to be 12.05. Thus 2-methyl-2-butene is considerably more soluble in furfural than pentene-2 and the difference is much more pronounced than the difference in the vapor pressures of the two olefins. The discovery that branched olefins possess a higher natural solubility in furfural than do close-boiling less-branched olefins is the basis for practical application of the process described herein to the separation of olefins in accordance with the present invention.

Example

In an example illustrating separation of 2-methylbutene-2 from pentene-2, n-pentane and lighter hydrocarbons, a feed having the composition

	Mol per cent
2-methyl-2-butene	9
Pentene-2 (mixture of isomers)	17
n-Pentane	40
Lighter than n-pentane	34
	100

is subjected to vapor-liquid extraction in an efficient column with about 20 moles furfural (containing 4 weight per cent water) per mole of hydrocarbon feed at a pressure of about 2 atmospheres absolute and a temperature of about 150° F. A reboiler partially strips hydrocarbons from the furfural reaching the kettle of the column so that the vapor load at the feed tray is approximately twice the feed. The rich furfural discharged from the extraction tower is then stripped in a stripping column at reduced pressure and/or increased temperature; the overhead product is a hydrocarbon stream containing

	Mol per cent
2-methylbutene-2	53
Pentene-2	27
n-Pentane	12
Lighter than n-pentane	8

This stream, which amounts to only about 15 per cent of the feed, contains nearly 90 per cent of all the 2-methylbutene-2 in the feed. The overhead from the extraction tower contains about 75 per cent of the pentene-2 and 95 per cent of the n-pentane in the feed.

Similar operations are applicable to the separation of such mixtures as isobutene and butene-1, and 2-methyl-1-butene and pentene-1.

Because the invention may be practiced other

wise than as specifically shown herein, and because many modifications and variations of it will be apparent to those skilled in the art, it should not be restricted except as specifically indicated in the following claims.

I claim:

1. A process for the resolution of a mixture of close-boiling structurally isomeric aliphatic olefins having from four to six carbon atoms per molecule and being of different degrees of branchedness into a fraction of more highly branched olefins and a fraction of less highly branched olefins which comprises extracting said mixture of olefins in the gaseous phase with a solvent composed of liquid furfural containing 3 to 5 weight per cent of dissolved water and thereby effecting preferential dissolution in the furfural of the more highly branched olefin content of said mixture while causing the less highly branched olefin content of said mixture to remain undissolved, separating the resulting solution from the resulting gaseous phase, and recovering the dissolved more highly branched olefins from said solution by stripping the same.
2. The process of claim 1 wherein said extracting is conducted at a temperature of from 50° to 300° F. and at a pressure below the vapor pressure of said mixture at the temperature of extraction.
3. The process of claim 1 in which the more highly branched olefin content of said mixture boils at a temperature of not more than 6 degrees F. below the less highly branched olefin content.
4. The process of claim 1 wherein the olefin content of said olefin mixture is composed of isobutene and butene-1.
5. The process of claim 1 wherein the olefin content of said olefin mixture is composed of 2-methyl-2-butene and pentene-2.
6. The process of claim 1 wherein the olefin content of said olefin mixture is composed of 2-methyl-1-butene and pentene-1.
7. The process of claim 1 wherein the olefin content of said olefin mixture is composed chiefly of aliphatic pentenes, the more highly branched pentene boils not more than 6 degrees F. below the less highly branched pentene, and wherein the mixture also contains a substantial amount of pentane which appears in the resulting gaseous phase in admixture with the less highly branched pentene.
8. The process of claim 1 wherein said furfural is employed in a mol ratio to said mixture of from 5:1 to 40:1.

CHARLES E. WELLING.
